UNITED STATES PATENT OFFICE.

JACQUES SCHNEIDER AND FREDERIC BILLON, OF SOLOTHURN, SWITZERLAND.

HIGH-TENSION DISTRIBUTER FOR INTERNAL-COMBUSTION ENGINES.

1,337,966.

Specification of Letters Patent. Patented Apr. 20, 1920.

Application filed October 19, 1918. Serial No. 258,914.

To all whom it may concern:

Be it known that we, JACQUES SCHNEIDER and FREDERIC BILLON, both citizens of the Swiss Republic, and both residing at Solothurn, Switzerland, have invented certain new and useful Improvements in High-Tension Distributors for Internal-Combustion Engines, of which the following is a specification.

10 The improved construction of high tension distributors that forms the subject-matter of the present invention allows of considerably reducing the space required for building-in the distributor, so that the 15 distributor need not necessarily be overhung but may be built-in at any suitable point. This improved construction of the distributor affords important advantages from the manufacturing as well as the working point 20 of view.

The essential feature of the improved construction consists in this that the fixed leads leading to the sparking plugs are arranged in two separate holders embracing 25 the two lateral sides of the revolving distributor part, in such a manner that the said leads are located right and left of the said revolving part and are not inclined, or only very slightly inclined, to each other 30 and so as to leave the upper and lower sides of the distributor free from leads. This improved arrangement effects a great saving in space compared to the hitherto usual construction wherein the leads are arranged 35 at equal angular distance around the entire periphery of the apparatus or around the upper half of the same. At the same time, the advantage from a manufacturing and working point of view is gained that the 40 holders can be made of one and the same pattern for both sides and can be interchanged as desired.

Some constructional forms of high tension distributors according to this invention 45 are illustrated by way of example in the accompanying drawings, in which:—

Figures 1 and 2 illustrate a distributor for a four-cylinder engine. The revolving part *d* composed of insulating material contains the contacts *e* which are arranged out of line with each other in the axial direction and inclose an angle $\alpha=90^\circ$ with each other in the circular direction; these contacts *e* are connected to the high tension coil of the 55 apparatus. The exit leads *g* with the exit

contacts *f* are arranged side by side in the axial direction in pairs, one pair in each of the holders *a* and *b* in such a manner that the two pairs are situated diametrically opposite each other. The two holders *a* and *b* are separated from each other and fixed by means of the spacing piece *c*.

The arrangement shown in Figs. 3 and 4 is suitable for a six-cylinder engine. The corresponding parts are indicated in these 65 and the following figures by the same letters as in Figs. 1 and 2. The leads *g* are mounted in two groups of threes in the holders *a* and *b* respectively and so arranged that in each group two lead contacts are 70 contacted in succession by one of the contacts *e* inclosing an angle $\alpha=60^\circ$, whereas only one lead contact is contacted by the other contact *e*.

Figs. 5 and 6 illustrate an arrangement 75 for an eight-cylinder engine. In this arrangement the leads *g* are attached in two groups of fours to the holders *a* and *b* respectively. The two pairs of leads of each group are arranged at an angle $\beta=45^\circ$ to 80 each other. The contacts *e* are shifted around through 90° to each other.

Figs. 7 and 8 and Figs. 9 and 10 show constructions suitable for twelve-cylinder engines. In Figs. 7 and 8 the six leads are 85 arranged in two groups of three pairs each, the three pairs of each group being spaced apart at equal angles $\beta=30^\circ$. The two contacts *e* are spaced apart circularly at an angle $\alpha=90^\circ$.

In Figs. 9 and 10 the six leads on each side are arranged in two groups of threes at an angle $\beta=30^\circ$ between the groups. Correspondingly to the leads which are arranged in three planes at right angles to the 95 axis, three contacts *e* are mounted in this case in the revolving part and they are spaced at angles of 120° .

The constructions shown in these figures are given by way of constructional examples of the invention, which may obviously be modified in view of the fact that the leads *g* which are arranged side by side in the axial direction may, together with the contacts *f*, likewise be shifted around through 100 any desired angle to one another. In such a case the angles α through which the contacts *e* are shifted relatively to one another in the circular direction must be modified 105 to correspond.

Having now described our invention, what we claim as new and desire to secure by Letters Patent is:—

1. In a high tension distributor for internal combustion engines comprising a cylindrical insulated rotating element carrying high tension leads connected to contacts arranged in varying angular positions on the surface of such cylindrical body, the combination with a pair of divided insulated segments partly surrounding the said cylindrical element and concentric therewith, having contacts on their inner faces arranged in pairs around and in line with the contacts of the rotating element in varying planes connected by leads to sparking plugs, substantially as set forth.
2. In a high tension distributor for internal combustion engines, comprising a cylindrical insulated rotating element carrying high tension leads connected to contacts arranged in varying angular positions on the surface of such cylindrical body in combination with a pair of interchangeable segments partly surrounding and concentric with the rotating element having gaps at their upper and lower sides, free from leads, the upper gap provided with a fixing spacing piece inserted between said segments, substantially as set forth.
